SAVINGS BANK ATTACHMENT

Harry S. Goodman, Chicago, Ill., assignor to
Jerome B. Arenson, Chicago, Ill.

Application May 3, 1934, Serial No. 723,628

5 Claims. (Cl. 40—62)

My invention relates to attachments for savings banks and more particularly to a novel attachment for a savings bank of book form which can be readily applied to and removed from the banks so that a salesman can demonstrate the device on any one of a number of banks.

My attachment contemplates the provision of a scale for calculating the results obtained by saving a definite amount per day, although of course, the particular details of the scale compilations may be varied to fit any particular case.

I will describe the preferred form of my invention by reference to the accompanying drawings wherein—

15 Fig. 1 is a perspective view of the device applied to a book bank;

Fig. 2 is a section on the line 2—2 of Fig. 1;
Fig. 3 is a section on the line 3—3 of Fig. 1;

Fig. 4 shows a modified form of attachment.

20 Referring now in detail to the drawing, the book bank is indicated by the numeral 5 and my attachment is indicated generally by the numeral 6.

6. Book banks of this character are really metal containers made to imitate a book in appearance 25 and are well known on the market at the present time.

It will be noted that in these book banks, the side edges such as 7 and 8 project beyond the end portions 9 and 10 which correspond to the 30 edges of the leaves in the book. My attachment 6 consists of a sheet of metal which has the side edges doubled over as indicated at 11 and 12 to form a channel receiving the slide 13 and guiding it at both edges.

35 Behind the slides 13 there is mounted the chart or scale 14 which is held in place by the slide and by the means such as 15 and 16 cooperating with the slide. Obviously, of course, this chart 14 may be otherwise secured, but the means 15 and 16 40 preferably should extend out far enough to prevent the slide 13 from escaping at the ends of the channels 11 and 12. The ends of the metal strip are bent over as indicated at 17 at the bottom and 18 at the top. The portion 17 is substantially 45 longer than the portion 18 and is curved outwardly as indicated at 19, while the portion 18 is hooked over rather sharply so as to form a hook for receiving the edge 7 of the bank. The attachment is applied in the following fashion:

50 First, the hook 18 is hooked over the top edge 7, and then the entire attachment is moved toward the side of the bank so as to cause the tip 19 to spring over the lower edge 8 of the bank and thus bring the member 17 over this lower edge under tension sufficient to hold the attach-

ment in position while the slide and the chart or scale are being used or demonstrated. When it is desired to remove the attachment, it is only necessary to pull outwardly on the attachment at the bottom thereof, and the member 17 will slide 5 off the lower edge of the bank.

The slide 13 is slotted as indicated at 20 to permit reading the numbers on the chart as the slot is moved up or down.

In the modified form of the invention shown in 10 Fig. 4, the plate 6' has the end portions 17' and 18' like the preferred form, but the slide 13' instead of being guided in grooves as in the main form is provided with the bent-over side portions 21 and 22 which fit over the side edges of plate 15 6'. The remainder of the parts may be the same as in Figs. 1-3. Thus it is evident that the slide 13' may be adjusted lengthwise of plate 6' in the same manner as slide 13 is adjusted on plate 6.

Having thus described one specific form of my 20 invention, what I claim as new and desire to secure by Letters Patent is:

1. An information giving attachment for savings bank containers and the like comprising a thin plate having two opposite side edges formed 25 with grooves opening toward each other, the surface between said grooves having a chart of information thereon, a slide having portions fitting in said grooves to guide the slide in movement and having a transverse slot therein for facilitating reading of the chart information, said plate having clip means for temporarily fastening the plate to the containers, said clip means comprising integral portions of said plate at opposite ends thereof bent over to snap onto the 30 edges of the containers.

2. An information giving attachment for savings bank containers and the like comprising a thin plate having two opposite side edges formed 40 with grooves opening toward each other, the surface between said grooves having a chart of information thereon, a slide having portions fitting in said grooves to guide the slide in movement and having means thereon for facilitating reading of the chart information, said plate having 45 clip means for temporarily fastening the plate to the containers, said clip means comprising a portion of the plate at one end of the plate bent over to form a hook on the side thereof opposite the chart, and a portion of the plate at the other 50 end thereof extending away from the main body of the plate on the side opposite the chart at an angle of slightly less than a right angle with an out-turned end whereby it may be snapped over the container edge. 55

3. An information giving attachment for savings bank containers and the like comprising a thin plate having two opposite side edges formed with grooves opening toward each other, the surface between said grooves having a chart of information thereon, a slide having portions fitting in said grooves to guide the slide in movement and having means thereon for facilitating reading of the chart information, said plate having 5 clip means for temporarily fastening the plate to the containers, said clip means comprising integral portions of said plate at opposite ends thereof bent over to snap onto the edges of the containers, said plate having projections at the 10 ends to hold the slide in said grooves.
4. An information giving attachment for book banks comprising a plate having means at two opposite edges adapted to snap over the edges of the bank to removably secure the plate thereon, 15 said means comprising an integral portion of said plate at the one edge extended and bent over to form a hook and an integral portion at the opposite edge extending away from the main body of the plate at an angle of slightly less than a right angle with an outturned end, said plate having a chart thereon on the side opposite said means.
5. An information giving attachment for book banks comprising a plate having means at two opposite edges adapted to snap over the edges of the bank to removably secure the plate thereon, 20 said means comprising an integral portion of said plate at the one edge extended and bent over to form a hook and an integral portion at the opposite edge extending away from the main body of the plate at an angle of slightly less than a right angle with an outturned end, said plate having a chart thereon on the side opposite said means, and said plate having a slide movable up and down thereon, said slide having means thereon facilitating the reading of the chart information.

the opposite edge extending away from the main body of the plate at an angle of slightly less than a right angle with an outturned end, said plate having a chart thereon on the side opposite said means.

5. An information giving attachment for book banks comprising a plate having means at two opposite edges adapted to snap over the edges of the bank to removably secure the plate thereon, 10 said means comprising an integral portion of said plate at the one edge extended and bent over to form a hook and an integral portion at the opposite edge extending away from the main body of the plate at an angle of slightly less than a right angle with an outturned end, said plate having a chart thereon on the side opposite said means, and said plate having a slide movable up and down thereon, said slide having means thereon facilitating the reading of the chart information.
